The ornamental design for a double ended lamp reflector kit, as shown and described.

DESCRIPTION

FIG. 1 is a perspective view of a doubled ended lamp reflector kit, as viewed from below, showing my new design;

FIG. 2 is a left side view of the kit shown in FIG. 1;

FIG. 3 is a right side view of the kit shown in FIG. 1;

FIG. 4 is a front elevation view of the kit shown in FIG. 1;

FIG. 5 is a rear elevation view of the kit shown in FIG. 1;

FIG. 6 is a top plan view of the kit shown in FIG. 1; and,

FIG. 7 is a bottom plan view of the kit shown in FIG. 1.

The broken lines in the drawings illustrate portions of the double ended lamp reflector kit which form no part of the claimed design.
